UNITED STATES PATENT OFFICE.

JOHN W. EHNINGER, OF SARATOGA SPRINGS, NEW YORK.

DESIGN FOR A STATUETTE GROUP.

SPECIFICATION forming part of Design No. 16,389, dated November 24, 1885.

Application filed September 2, 1885. Serial No. 176,039. Term of patent 3½ years.

To all whom it may concern:

Be it known that I, JOHN WHETTEN EHNINGER, a citizen of the United States, residing at Saratoga Springs, in the county of Saratoga and State of New York, have invented and produced a new and original Design for a Statuette Group, to be cast in plaster, bronze, or any other suitable material, of which the following is a specification, reference being had to the accompanying photograph, forming part thereof.

My design consists of a group of two figures (male and female) in the act of descending a "chute" or inclined plane on a "toboggan" or Canadian sledge. Both figures are clad in the costumes usually worn by Canadians when engaged in this pastime, viz.: the woman is dressed in a tight-fitting body, with full skirt, the whole trimmed with fur; the man in a double-breasted coat of blanket or other coarse material, a sash around his waist, knee-breeches and coarse stockings. Both wear mittens on their hands, moccasins on their feet, and a cap on the head, made of knit

worsted, with a peak hanging down behind. 25 The female figure is seated in front, with her feet resting upon that part of the toboggan which is turned up in front. Her hands are grasping the rail on either side. She is slightly leaning over toward the left side, and 30 her face is upturned and slightly inclined toward that of the male figure. He is seated behind the woman, with his left leg bent under him, his right leg extended, with the toe touching the surface of the slide, his hands 35 grasping the rails behind those of the female figure, whose head rests lightly on his left shoulder.

I claim—

The design for a statuette, consisting of a 40 group of figures herein shown and described, representing a woman seated upon a cushioned toboggan and a man behind her guiding the same.

JOHN W. EHNINGER.
